UNITED STATES PATENT OFFICE.

WOLDEMAR REINHOLD HEINITZ, OF CHEMNITZ, GERMANY, ASSIGNOR TO THE FIRM OF SCHUBERT & SALZER MASCHINENFABRIK, AKTIENGESELLSCHAFT, OF CHEMNITZ, GERMANY.

CASH-REGISTER.

No. 869,084.

Specification of Letters Patent.

Patented Oct. 22, 1907.

Application filed May 14, 1907. Serial No. 373,611.

To all whom it may concern:

Be it known that I, WOLDEMAR REINHOLD HEINITZ, a citizen of the Kingdom of Saxony, and a resident of Chemnitz, Germany, whose post-office address is Neefestrasse 24, have invented certain new and useful Improvements in Cash-Registers, of which the following is a specification.

My invention relates to cash registers presenting a plurality of tills, and has reference in particular to means for bringing into operative position the special counting, printing, indicating, adding, canceling, or other like devices employed besides the main counting, printing and indicating device. The number of special devices provided corresponds with the number 15 of tills, and the simple motion of the latter itself effects adjustment of the said devices.

The essential feature of my present invention is that in order to prevent the possibility of errors, the adjustment is effected with positive motion.

20 Certain forms of the invention are illustrated in the accompanying drawings.

Figure 1 is a vertical section through a portion of a register fitted with the new mechanism. Fig. 2 is a section through the same, seen from the back. Figs. 25 3 and 4 are similar views of a modified construction. Fig. 5 is a sectional view showing tills provided with another form of device.

In the case 1 of the register there is mounted the main shaft 2 which carries the adjusting disks 4, set in 30 well-known manner by the keys 3. The shaft 2 is rotated by the crank 5; on it are mounted a toothed segment 6 and a cam disk 7. Parallel with the shaft 2 there is another shaft 8, on which are mounted two toothed segments 9 and 10. The segment 10 lies in 35 the plane of the segment 6, so that on rotation of the main shaft 2 the two segments intermesh.

To the segment 9 there is jointed a rod 11, which extends almost to the bottom of the register. The tills 12 are furnished at the back with pairs of projections 40 or fingers 13, which are chamfered in opposite directions so as to present a gap 14. The rod 11 presents studs 15 located on a level with the gaps 14.

The special devices 17 for counting or the like are mounted in a slide 16, which at one side is provided 45 with a rack 18, which can be brought into engagement with the segment 9.

20 is a spring-controlled bolt, mounted in a suitable bracket 19 and actuated by the cam 7. The slide 16 presents notches 21, which the bolt 20 can enter.

50 22 is the main counting mechanism, which is likewise operated by the adjusting disks 4.

The operation of the apparatus is as follows:—After depressing the keys to register the value desired, the cashier pushes in the till allotted to him. Since each of the studs 15 on the rod 11 lies on a level with a chamfered finger 13, the stud 15 of the receded till will be caused by the finger 13 to rise and enter the gap 14. In this position of the stud 15 further motion of rod 11 is impossible. As, however, the chamfers present different angles of inclination, the rod 11 will be more 55 or less elevated, depending upon which chamfered finger 13 actuates it. This motion of the rod is transmitted by the segment 9 to the slide 16, and so sets the correct special mechanism 17, that the adjusting disk 4, on the crank being now turned, can act upon it. In 60 order that the slide may not shift during this rotation, the bolt 20 at the commencement of the crank rotation is depressed into one of the notches 21 by the cam 7 and can only snap up again under the action of its spring, after the rotation of the crank has ended. 65 Hereupon the segment 6 meshes with the segment 10 and returns the slide 16 and rod 11 to their initial position.

The slide may be operated in various ways. Figs. 3 and 4 show, for example, that, if desired, special 70 rods can be provided for each till, two, 11 and 11¹, being furnished in the present case for each till, the rods being jointed to a cross-piece 23 on the shaft 8. Instead of two fingers 13 as in Figs. 1 and 2, only one finger 24 is provided here, presenting two flat surfaces 75 or rests 25, 25¹ at different levels, separated by an inclined plane 26. On a till being pushed in, the front-rod 11 ascends the incline 26. When it reaches the rest 25, the rod 11¹ will repose on the rest 25¹, so that further motion is impossible. The proper extent of 80 motion of the slide 16 is caused by the fingers 24 and the incline 26 being unlike.

Fig. 5 shows a modification in which in place of two fingers on each till, as in Figs. 1 and 2, with a single stud 15 entering between them, there is only one finger 13 85 which slides between two studs 15, 15¹ on the rod 11. In other respects the arrangement is the same as that already described.

Having thus described my invention, I claim as new:—

1. In a cash register, in combination, a plurality of sliding tills; a special counting or indicating mechanism for each till; and means, operating with positive motion, actuated by recession of the tills, for bringing the special mechanism corresponding to the receded till into the operative position, substantially as described.

2. In a cash register, in combination, a plurality of sliding tills, a slide provided with a rack at one side, special

counting or indicating devices for the tills mounted in the said slide and a toothed segment meshing with the rack on the said slide, a pair of chamfered fingers at the back of each till, a vertically sliding rod jointed to the said toothed segment and presenting a series of studs, normally lying on a level with the chamfer of the lower finger of the said pair of fingers and entering the gap between the latter by recession of the corresponding till, whereby the said sliding rod is elevated and the said toothed seg-

ment turned, so that the special device corresponding to 10 the recessed till is brought into the operative position; substantially as described.

The foregoing specification signed at Chemnitz this thirtieth day of April 1907.

WOLDEMAR REINHOLD HEINITZ.

In presence of—

ERNST JOHANNES ZEUNER,
FREDERICK J. DIETZMAN.
